UNITED STATES PATENT OFFICE.

EDGAR H. BETTS, OF TROY, NEW YORK, ASSIGNOR TO EARL & WILSON, OF TROY,
NEW YORK, A CORPORATION OF NEW YORK.

COLLAR.

1,282,729.

Specification of Letters Patent. Patented Oct. 29, 1918.

Application filed December 20, 1917. Serial No. 208,162.

To all whom it may concern:

Be it known that I, EDGAR H. BETTS, a citizen of the United States, residing at Troy, in the county of Rensselaer and State of New York, have invented certain new and useful Improvements in Collars, of which the following is a full, clear, and exact description.

This invention relates to collars of the so-called turn-down or fold type, particularly soft collars, and its object, briefly stated, is to provide a collar of simple construction, which can be manufactured at low cost and yet be as good or even better in appearance than collars made in accordance with the prevailing practice.

In the preferred method of practising my invention the band, that is, the part which is adjacent to the wearer's neck when the collar is worn, can be made in the usual way, by placing two blanks together, with or without an intermediate layer or ply; or it may be made of a single layer composed of fabric of suitable body. The outer portion or top, that is, the part which is turned or folded down on the outside of the band, is made of a plurality of plies which are interwoven with each other but has a thin edge which is inserted into or laid upon the top-edge of the band. The two are then stitched, and the aforesaid thin edge of the outer portion then acts as a hinge, on which said portion can be folded easily and accurately.

Referring now to the accompanying drawing, in which one embodiment of the invention is illustrated,

Figure 1 is a plan view of the outer portion of the collar.

Fig. 2 is a plan view of the collar band.

Fig. 3 is a diagrammatic plan view of the band and outer portion assembled.

Fig. 4 is a diagrammatic cross section of the finished collar, say on line 4-4 of Fig. 3.

Fig. 5 is a diagrammatic cross section of a fabric for the outer portion of the collar.

Fig. 6 is a plan view of the fabric, showing the layout of the blanks to be cut therefrom.

The band 10 is made in the usual manner, and is composed of two outside layers 11, 12, with their edges turned in, the upper edge 13 being left open. The material for these two layers can be relatively inexpensive since it is practically concealed when the

collar is worn. Usually the band has one or more intermediate plies of cheap fabric to give more body and stiffness, but to avoid confusing the drawings the intermediate plies are not shown.

The outer portion or top 14 is composed of two outer layers 15, and, preferably, one or more inner layers or plies. One such inner layer is shown at 16. The several layers composing the outer portion of the collar are "integral" with each other, so to speak; that is, they are interwoven with each other. The weaving of such multiple fabrics is well understood in the textile arts and need not be described in detail here. Suffice it to say that, in general, as many layers of warp are used as there are to be "plies" in the fabric, and the weft threads are interwoven into the several warp-layers. At what is to be the upper edge of the outer portion or top the fabric is thinned, as by omitting one or more of the warp-layers, so that a thin selvage 17 of suitable width is formed. Or, preferably, the fabric is woven in a wide piece with a thin strip down each edge, as 18, and one or more intermediate thin strips 19. A thread of contrasting color can be woven down the center of each intermediate strip, as indicated by the dotted lines 20, to serve as guides in cutting the fabric. The blanks for the outer portions or tops 14 can be cut out as indicated in Fig. 6, or any other convenient and economical lay-out can be used.

The thin edge of the interwoven outer portion or top is inserted into the open top edge of the band as shown in Fig. 3, and the two are united by one or more rows of stitching, as 21, Fig. 4. The said thin edge is by preference straight and the upper edge of the band curved, as indicated in Figs. 1 and 2, respectively, but in joining the two parts, the straight edge of the outer portion or top is made to follow the contour of the curved edge of the band, as shown in Fig. 3, so as to produce a tendency to curl. Then when the outer portion or top is folded down the whole collar will tend to assume a more or less circular form. A sufficient width of the thin edge is left outside of the band to serve as a hinge on which the outer portion can be folded down upon the band.

It is to be understood that the invention is not limited to the specific form herein illus-

trated and described, but can be embodied in other forms without departure from its spirit as defined by the following claim.

I claim:

- 5 A fola or turn-down collar comprising a band forming the inner portion of the collar, said band having its upper edge curved; and an outer portion composed of a plural-

ity of interwoven layers or plies and woven with a straight thin edge, the latter being 10 secured to the curved upper edge of the band and conforming to the curvature thereof.

In testimony whereof I hereunto affix my signature.

EDGAR H. BEITS.
